UNITED STATES PATENT OFFICE

156,601

COMBINATION CIGARETTE HOLDER, ASH TRAY, AND LIGHTER

Angelo Mario Calcagno, Brooklyn, N. Y.

Application August 29, 1947, Serial No. 141,115

Term of patent 7 years

(Cl. D85—2)

To all whom it may concern:

Be it known that I, Angelo Mario Calcagno, a citizen of the United States of America, residing at Brooklyn, county of Kings, State of New York, United States of America, have invented a new, original, and ornamental Design for a Combination Cigarette Holder, Ash Tray and Lighter, of which the following is a specification, reference being had to the accompanying drawing, forming part thereof.

I claim:

The ornamental design for a combination cigarette holder, ash tray and lighter, as shown.

ANGELO MARIO CALCAGNO.
